UNITED STATES PATENT OFFICE.

WILLIAM D. ADAMS, OF NEW YORK, ASSIGNOR TO HENRY BLENDERMANN AND JACOB BLENDERMANN, OF NEW YORK, JOHN CUMMISKEY, OF BROOKLYN, AND SOPHIE E. ADAMS, OF NEW YORK, N. Y.

STEAM-GENERATOR.

SPECIFICATION forming part of Letters Patent No. 340,408, dated April 20, 1886.

Application filed February 13, 1886. Serial No. 191,791. (No model.)

To all whom it may concern:

Be it known that I, WILLIAM D. ADAMS, of the city and county of New York, in the State of New York, have invented a new and useful Improvement in Steam-Generator Furnaces, of which the following is a specification.

My invention is applicable to furnaces of steam-generators which comprise two cylindric boiler structures, or boilers provided with 10 heating flues or tubes so arranged and connected one above another in a setting that the products of combustion, after passing rearward under the first or lower boiler and forward through the tubes or flues thereof, pass 15 thence rearward under the upper boiler and between the upper and lower boilers.

The object of my invention is to afford simple provision for introducing between the two boilers a proper quantity of heated air to mingle with the unconsumed gases, as they pass 20 rearward between the boilers, and effect their combustion.

The invention consists in the combination, with the upper and lower boilers, arranged 25 one above another and connected to provide for the water-circulation from one to the other of them, of a setting for the boilers, including a furnace below the lower boiler, and sheet-flues, or flues having height and length, but 30 little width or thickness, constructed in the side walls of the furnace, and having an inlet or inlets for fresh air, and series of outlet holes or openings arranged lengthwise of and at a point between the boilers, whereby the 35 heated air delivered in jets or streams along the path of the products of combustion, as they pass between the boilers, will be caused to mingle with the unconsumed gases and effect their consumption.

40 In the accompanying drawings, Figure 1 is a vertical longitudinal section of a steam-generator embodying my invention; and Fig. 2 is a vertical transverse section on the plane of the dotted line α α , Fig. 1.

45 Similar letters of reference designate corresponding parts in both figures.

The generator here chosen to illustrate my invention consists, essentially, of a lower boiler, A, and an upper boiler, B, both of which

are of cylindrical form, and contain heating 50 flues or tubes. These boilers are connected by a throat, B', which provides for circulation from one to the other of them, and which is here shown as near their front end. At their opposite or back ends is a saddle, B'', superposed on the lower boiler, and on which the upper boiler, B, is supported and may move as its expansion may be greater or less than that of the lower boiler.

The boilers A B are arranged in a setting 60 comprising a front, C, and brick-work C'.

D designates the furnace, having a grate, a, and fire and ash-pit doors b c, and in the setting are partition-plates or deflectors d e f, whereby the products of combustion are caused 65 to take the direction indicated by arrows in Fig. 1 in their passage from the furnace to the chimney-outlet E.

From the furnace D the products of combustion pass over the bridge-wall D' rearward 70 under the boiler A, thence forward through the tubes or flues of the lower boiler, A, to the front thereof, thence rearward between the boilers and forward through the tubes or flues of the upper boiler, B, and, finally, rearward 75 over the upper boiler, B, to the chimney-outlet E.

I desire to introduce heated air between the upper and lower boilers, to there mingle with whatever hot gases may be still unconsumed, 80 and to thereby effect their combustion. To this end I construct, in the side walls of the setting, flues or heating-chambers F. These I term "sheet-flues," as they have considerable height and length, but little width or 85 thickness, as shown clearly in Fig. 2.

I have here shown openings or passages g at the rear of the setting, for the inflow of fresh air, and as the air is contained in these flues F in a thin sheet it will become rapidly heated. 90 At the upper part the flues F are provided with longitudinal series of outlet openings or ducts h, which are situated at a point between the boilers, and which extend nearly or quite the length thereof. The hot air, issuing in jets or streams through these outlet openings h along the path traveled by the products of combustion, mingles with the uncon-

sumed gases and supplies the oxygen necessary for their combustion, thereby preventing their escape in an unconsumed state.

By the term "cylindric boilers," as herein used, I do not mean that the vessels A B must be truly cylindric, but only intend to refer to the type of structure of which they are examples.

The generator composed of the boilers A B, arranged and connected as described, and the partitions or deflectors, whereby the products of combustion are caused to take the course indicated by arrows, are not here claimed, as they form the subject of my application Serial No. 189,908, filed January 27, 1886.

What I claim as my invention, and desire to secure by Letters Patent, is—

The combination, with upper and lower boilers arranged one above the other and connected for circulation, as described, of a setting including a furnace below the lower boiler and sheet-flues constructed in the side walls of the furnace and having an inlet or inlets for fresh air and series of outlet holes or openings arranged lengthwise of and between the boilers, whereby heated air will be discharged to mingle with the unconsumed gases as they pass between the boilers, substantially as herein set forth.

WILLIAM D. ADAMS.
